JAMES C. UPHAM, OF NORTH SYDNEY, AND JOHN P. ROGERS, OF ELMSDALE,
NOVA SCOTIA, CANADA.

ELECTRIC RAILWAY-SIGNAL.

SPECIFICATION forming part of Letters Patent No. 293,381, dated February 12, 1884.

Application filed March 12, 1883. Renewed December 8, 1883. (No model.)

To all whom it may concern:

Be it known that we, JAMES C. UPHAM, of North Sydney, in the county of Cape Breton, Province of Nova Scotia, and Dominion of Canada, and JOHN P. ROGERS, of Elmsdale, in the county of Hants, Province of Nova Scotia, and Dominion of Canada, have invented certain new and useful Improvements in Electric Railway-Signals, of which the following is a full, clear, and exact description.

The object of our invention is to provide for giving signals upon railway-trains approaching each other within certain limits, so that the engineer of any one train shall be notified in case there is another train at the front or rear within such limits. To that end we provide the road-bed with electric conductors connected together to form blocks of any suitable length in addition to the rails, which are arranged as continuous conductors, and upon the engines we provide batteries, electric-signaling apparatus, and circuit-closing devices, whereby the proper signals shall be given at the time required. We further provide devices for reversing the batteries, which may be required in certain contingencies, all as set forth more particularly herein-after.

Reference is to be had to the accompanying drawings; forming part of this specification, in which similar letters of reference indicate corresponding parts in all the figures.

Figure 1 is a diagram representing the axle of the locomotive and the arrangement of the signaling devices and reversing mechanism upon the locomotive. Fig. 2 is a side view of the circuit-closing device on the locomotive. Fig. 3 is a detail view, showing the arrangement of the conductors in the road-bed. Figs. 4 and 5 are diagram views, illustrating the track and electric conductors and the working of the apparatus in different positions of the trains.

A B in Figs. 1, 4, 5 are the rails of the track, arranged to serve as continuous electric conductors, and between these are the electric conductors *c d*, which are insulated from the supporting-ties of the rails. These conductors may be wires or metal rods, or they may be of strap metal. When of wire they may be supported by strips *h* of wood, as shown in

Fig. 3, and the wood will in that case be formed with a rounded top, and provided with a groove containing some insulating material, on which the wire will be placed and fastened by staples, as shown at *t*. The under part of the wooden support is hollow, so that in case of rain there will be no wet surfaces between the conductor and the supporting-legs *j*, which have their upper ends screwed into the wooden strip, and their lower ends fastened to the sleepers, as shown. The wood may be tarred or painted, and the hole for the leg *j* may be filled with some insulating material before it is inserted, so as to preserve the insulation. At certain intervals, which may be any distance desired, the continuity of the separate conductors *c* and *d* is broken, and they are connected by cross-connections *c'*. These cross-pieces should be of heavy insulated wire, of wrought or strap metal, and to secure them from injury they may be laid beneath the surface of the ballast. Each engine carries a battery or other source of electric power, (represented at *E* in Fig. 1,) also two electro-magnetic signaling-instruments, *W* and *W'*, and the instrument *W'* is provided with an attachment for giving a special additional signal when acted upon by the combined power of the batteries. There is also upon the engine an arrangement for making contact with the conductors *c d*. This may be either a sliding contact pressed down by a spring, or it may be a rolling or wheel contact by a wheel upon the end of an arm bearing upon the conductors.

In Figs. 1 and 2 *f f'* are contact devices, made in the form of paddle-wheels, the edges of the paddles being made somewhat sharp, so as to cut through any light covering of snow, ice, or dust. The wheels are supported by frames *S*, which are hinged at *f'* to and insulated from upper frames, *R*. In addition to the paddle-wheels, brushes may be used.

The signaling-instruments may be of any ordinary character—such as vibrating alarm-bells—and, if desired, there may be a visual signal in connection with them in the form of an index.

The batteries should be of a character to give a current of considerable quantity at a low potential, so as to work the signals with a good degree of force and lessen the tendency

to leakage in wet weather. All the batteries have like poles in the same direction relative to conductors c and d , as shown in Figs. 4 and 5. For this purpose, in connection with each battery there is to be a reversing-switch of any suitable construction. At T in Fig. 1 is shown such a switch of simple construction. a b are two metal strips, connected by a bar, a' , of insulating material. i i' are two buttons, and k is a plate with which the arms a b make contact. The buttons are permanently connected to each other and to one of the segments of the arc u p , while the plate k is connected to the other conductor. This reversing-switch is to be moved only when the engine is turned upon a turn-table—that is to say, the switch must be reversed only when the heading-direction of the engine is changed, not the running-direction, in order that the zinc pole may remain in connection with the conductor c . There is also upon each engine an arrangement by which the position of the batteries is changed simultaneously with any change in the running-direction of the engine, (this arrangement is shown in Fig. 1,) so that the change is made automatically by the movement of the reversing-lever L of the engine, which in this figure is shown as at the center and as connected by a wire with the axle of the locomotive, for use as a switch-arm with the fixed segments n p , that are connected with the two poles of the battery by wires n' and p' , or, more exactly, with the sides of the battery-reversing device. In the position shown the lever L overlaps the end of the piece n , and remains in contact with that piece when moved to drive the engine forward; but whenever the reversing-lever is drawn back to change the running-direction the lever passes upon the segment p and the battery is reversed. The same change might be effected by any devices of suitable character. The sides of the reversing-switch will be marked "up" and "down," or with equivalent marks, and when the engine is headed up the road the handle of the reversing-switch will be turned to the "up" side and locked; but when the engine is turned upon the track the handle should be turned over to the "down" side.

In Fig. 1 the circuit is from conductor c by wire c' to bell W' , thence to segment n , lever L , and to the axle; and from conductor d by wire d' to bell W'' , and by wire d'' to the plate k of the reversing device, thence through the arm a to the battery, to the arm b to the button i' , thence by wire n' to the segment n . Both signaling-instruments are constructed and adjusted to give a signal when the current from one battery passes through their magnets. The instrument W' has a second magnet arranged to give an additional signal, either audible or visible, when acted upon by two batteries, or the same result may be obtained by using one magnet with a second armature, so adjusted as to respond only to the stronger current.

In the diagrams, Figs. 3 and 4, the lines

marked O represent the axles of the engine, the wheels of which are in contact with the rails. Supposing two engines to come into such a position that only one break in the conductors c d intervenes, the action is as follows: The line marked 2, Fig. 4, represents the forward engine, and the line marked 1 the engine following. The current in this case passes from the copper pole of the battery on engine No. 1, through the instrument W^2 of that engine to conductor d , by cross-connection c' to conductor c , through instrument W' of engine No. 2, and by the middle connection to the axle of engine No. 2, thence by wheels and rails to wheels and axles of engine No. 1, and by the middle connection to the zinc pole of the battery of engine No. 1, thus completing the circuit to the bell W^2 of the engine No. 1. By the ringing of the bell W^2 of engine No. 1 "danger ahead" is indicated, and by the ringing of the bell W' of engine No. 2 the warning of "danger behind" is given. I remark that the instrument W^2 always warns of danger from the direction of the cow-catcher, while instrument W' warns of danger from the direction of the tender, no matter whether the engine be running head forward or backing. This might be made plainer by having an arrow or index-hand placed over each instrument, pointing in the direction of the danger. These two engines Nos. 1 and 2, Fig. 4, are represented as moving in the same direction. Now, supposing two engines are moving in opposite directions, as represented at 3 and 4, Fig. 4, the operation is as follows: The current passes from the copper pole of the battery of engine No. 4 by middle contact to the axle, thence by wheels and rails to the wheels and axle of engine No. 3, thence by middle and left-hand connecting-wires n' and c' of that engine through instrument W' to conductor d , cross-connection c' , and conductor c , to and through the instrument W^2 of engine No. 4, and back to the battery, thus completing the circuit and giving the warnings as above. In case of opposing engines, as Nos. 2 and 3, Fig. 4, the current passes from the copper pole of the battery of engine No. 2, through instrument W^2 to conductor d by the cross-connection to conductor c , to instrument W^2 of engine No. 3, through the battery thereon and the middle connection to the axle and wheels of engine No. 3, thence by the rails to the wheels and axle of engine No. 2, and by the middle connection to the zinc pole of the battery of that engine, thus completing the circuit with two batteries combined, warning "danger ahead" on both engines, and by the double strength of the current operating the supplementary signal on both, indicating that the engines are opposing each other in the direction of movement.

Now, supposing the extreme position, where-in by a possibility opposing engines have come upon the same length of conductor c simultaneously, thus failing to get the usual signals. This is illustrated in Fig. 5 by en-

gines No. 1 and No. 2. As soon as both strike the respective ends of conductors *c* and *d*, the current passes from the copper pole of the battery of engine No. 1, through its instrument *W*², to conductor *d*, to instrument *W'* of engine No. 2, through the middle connection, axle, and wheels of engine No. 2, by the rails to the wheels and axles of engine No. 1, and by the middle connection back to the zinc pole of the battery, thus completing the circuit and warning both engines. At the same time the current from the copper pole of the battery of engine No. 2 passes through the middle connection, axle, and wheels, and by the rails to the wheels and axle of engine No. 1, and through the middle connection to the instrument *W'*, thence by the left-hand connection to the conductor *c*, and by the wire *d'* to the instrument *W²* of engine No. 2, back to the zinc pole of its battery, thus completing the second circuit and warning both engines. It will be seen that in this peculiar position both engines are warned by a special signal, consisting of a simultaneous alarm on both instruments, but without the extra signal of instrument *W²*. If, now, by a possibility another engine following one of these, as represented at 3 in Fig. 5, should come within warning distance, the action would be to warn engine No. 3 of "danger ahead" in the usual manner; but on engine No. 2 the signal would cease on instrument *W'*. This may be seen from the action of the current, as follows: It is, to be remembered that a current from the battery of engine No. 1 is already passing through instrument *W'* of engine No. 2 from left to right. When engine No. 3 comes upon the block, the current passes from the copper pole of its battery through the middle connection, axle, and wheels, by the rails to the wheels and axle of engine No. 2, thence by the middle connection through instrument *W'* of engine No. 2 from right to left, through the conductor *d*, by the cross-connection *c'*, to the instrument *W²* of engine No. 3, back to the zinc pole of the battery, thus completing the circuit and warning engine No. 3 by the instrument *W²*; but as the instrument *W'* on engine No. 2 is now acted upon by equal opposing currents, its signal ceases, that of *W²* still continues; but as it lacks the supplementary or extra current feature, the driver may know just the situation of affairs at once. If, now, engine No. 1 were to back off down the track, the "danger ahead" signal upon *W²* of No. 2 would cease until No. 1 had passed the section-brake or cross-connection, when it would be renewed. When No. 1 moved backward, *W'* on No. 2 would again commence to signal "danger behind" on engine No. 2, its silence up to this time having already warned of the presence of engine No. 3. These various signals, although apparently compli-

cated, may be readily understood by a brief set of instructions; but, if desired, a special code for communication and telephone or telegraph instruments may be provided upon the engines.

There is one other possible situation not yet mentioned illustrated by engine No. 4 in Fig. 5, where such engine, though heading up the road, is backing down, and thereby becomes a follower of engine No. 3, so that the battery upon engine No. 4 is switched into the position occupied by that of an engine headed down, this switching having been done automatically at the moment the reversing-lever was moved to change the running direction. In case an alarm should sound while the engine was standing on the track, the driver could easily inform the other that his own engine was stationary by moving the reversing-lever back and forth two or three times, which would have the effect of giving an intermittent signal.

We do not limit ourselves to the details of construction specified in the signal-instruments, circuit-closing device, or conductors, as they may be varied within the scope of our invention. The conductors *c* *d*, instead of being placed upon the ground, may be strung upon posts at the side of the track.

Our invention contemplates the use, as a source of electric power, of batteries of any known character, storage-cells, or dynamo-machines alone or combined.

The apparatus may be also arranged to prevent danger from open draws in bridges. This can be effected by a simple arrangement of the draw fixings, whereby on the draw being opened the rail or rails shall be put into electrical contact with conductor *c* or *d*, so that if an engine should come upon that section of *c* *d* a warning would be given. By inserting an instrument in circuit at the draw the keeper could receive warning of the approach of an engine, and could then give any usual signal to the engine.

Having thus described our invention, what we claim as new, and desire to secure by Letters Patent, is—

1. The paddle-wheel contacts *f*, having sharp edges, in combination with the supporting-frames *S*, hinged at *f'*, and insulated from the upper frames, *R*, as shown and described.
2. The combination on locomotives with the instruments *W* *W²*, and circuit-closers *f*, of the lever *L*, connected to the axle, segments *n* *p*, and connections *n'* *p'*, substantially as described, for bringing these instruments in direct connection with the axle, as set forth.

JAMES C. UPHAM.
JOHN P. ROGERS.
